(57) **CLAIM**

The ornamental design for the tongue-in-groove pliers, as shown and described.

DESCRIPTION

FIG. 1 is a perspective view of a tongue-in-groove pliers in accordance with an embodiment of the present invention; FIG. 2 is a left side view of the tongue-in-groove pliers of FIG. 1;

FIG. 3 is a right side view of the tongue-in-groove pliers of FIG. 1;

FIG. 4 is a front view of the tongue-in-groove pliers of FIG. 1;

FIG. 5 is a front view of the tongue-in-groove pliers of FIG. 1;

FIG. 6 is a top view of the tongue-in-groove pliers of FIG. 1;

FIG. 7 is a bottom view of the tongue-in-groove pliers of FIG. 1;

FIG. 8 is an isolated perspective view of a first half of the tongue-in-groove pliers of FIG. 1; and,

FIG. 9 is an isolated perspective view of a second half of the tongue-in-groove pliers of FIG. 1.

The broken lines in the drawings illustrate portions of the tongue-in-groove pliers that form no part of the claimed design.

1 Claim, 7 Drawing Sheets
